FIG. 1 is a perspective view of a key showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The dashed broken lines illustrate structure or features which form no part of the claimed design.

The dot-dash broken lines represent boundaries of the claimed design; the boundaries themselves form no part of the claimed design.

The gray surface shading in FIGS. 1-2 represents a metallic surface.
